UNITED STATES PATENT OFFICE.

CHRISTIAN BLANCARD, OF NEW YORK, N. Y.

DIAMOND-SETTING.

SPECIFICATION forming part of Letters Patent No. 325,485, dated September 1, 1885.

Application filed June 1, 1885. (No model.)

To all whom it may concern:

Be it known that I, CHRISTIAN BLANCARD, of the city, county, and State of New York, have invented certain new and useful Im-
5 provements in Diamond-Settings, of which the following is a specification.

This invention relates to an improved setting for diamonds and other gems; and the invention consists of a diamond or other setting in which the bezel at the base of the setting is made integral with the body of the same.

In the accompanying drawings, Figure 1 represents a top view of the blank from which 15 my improved diamond-setting is made. Figs. 2, 3, 4, and 5 are sectional side elevations, showing the setting in different stages of its manufacture; and Fig. 6 is a side elevation of a finished setting, partly in section.

20 Similar letters of reference indicate corresponding parts.

My improved setting for diamonds and other gems is made from a blank, a , having a disk-shaped center, a^2 , and radial arms a' , as 25 shown in Fig. 1. The center a^2 of the blank a is drawn by dies into cup-shape, simultaneously with bending up the radial arms, as shown in Fig. 2. A second set of dies elongates the cup-shaped center portion, a^2 , and 30 shapes the radial arms into cramps, as shown

in Fig. 3. By a third set of dies the bottom of the cup-shaped portion is punched out, and thereby a nearly cylindrical base for the setting obtained, as shown in Fig. 4. Another pair of dies upsets the lower cylindrical part 35 of the setting and bends it into a rim or bezel, b , at the base of the setting, as shown in Fig. 6.

A setting with such an upset rim or bezel, b , is neater and stronger than one in which the bezel has been soldered on, which is the method heretofore employed for fastening the bezel to the setting. By making the bezel integral with the body of the setting considerable time and labor are saved and a 45 durable and neatly-finished setting for gems obtained.

Having thus described my invention, I claim as new and desire to secure by Letters Patent—

A setting for diamonds and other gems, 50 having an upset rim or bezel made integral with the body of the setting, substantially as set forth.

In testimony that I claim the foregoing as my invention I have signed my name in presence of two subscribing witnesses.

CHRISTIAN BLANCARD.
